ART OF GLUING

Application filed February 24, 1932. Serial No. 594,857.

This invention relates to the art of gluing, and, more particularly, to processes for the formation of plywood.

An object of the invention is to provide an improved process for uniting a wood member and another member.

A further object is to provide an improved method for the formation of plywood.

Other objects of the invention will in part 10 be obvious and will in part appear hereinafter.

The invention accordingly comprises the several steps and the relation and order of one or more of such steps with respect to each 15 of the others thereof, which will be exemplified in the process hereinafter disclosed, and the scope of the application of which will be indicated in the claims.

For a fuller understanding of the nature 20 and objects of the invention reference should be had to the following detailed description taken in connection with the accompanying drawing, in which:

The figure illustrates somewhat diagrammatically a mode of procedure in accordance 25 with the invention.

The invention contemplates the provision 30 of an improved procedure for uniting a member composed of wood to a member formed of such material or other material. It is particularly adapted for the formation of plywood composed of two or more substantial layers, at least one of which is formed of wood. It is to be understood that the term 35 "wood" as used herein includes any porous material of a fibrous or cellular structure having sufficient body to permit the adhesive to obtain a firm grip thereon.

In the formation of such a product the provision 40 of an adhesive base in discrete-particle form at the glue line, possesses a number of advantages and various proposals to this end have been made, as, for instance, in various copending applications of Theodore Williams 45 Dike and others.

It is customary in the formation of plywood to place the assembly between pressure plates and to subject it to pressure, or to heat and pressure therein, in order to set the adhesive.

When the adhesive base is applied in discrete-particle form, many difficulties occur in obtaining the proper degree of plasticization and penetration before the final setting of the adhesive, and in properly correlating the 50 plasticization and setting factors. The difficulties in obtaining sufficient penetration are particularly marked in the use of difficultly plasticizable material such as casein, soya-bean flour, other oil-seed flours, etc.

In accordance with the present invention a 55 gluing procedure may be carried out in such a manner that these difficulties are reduced or avoided.

Certain of these difficulties result from a 60 premature setting of the adhesive before the same has been fully plasticized, i. e., brought into a sufficiently fluid state to properly penetrate the pores of the wood, so that, when the adhesive sets, forces tending to separate 65 the members will encounter resistance of a substantial body of the wood rather than merely the surface fibres which are easily pulled off. With a view to avoiding this and other difficulties, the invention contemplates 70 the removal of the assembly from the press after the formation of a preliminary bond sufficient to hold the members together while further plasticization and setting occur, and preferably discontinuing the application of 75 heat and pressure at a time when a layer of substantially independent particles remains between the members, (i. e., when there is 80 between the members a layer of discrete particles of the adhesive which present a sub- 85 stantially unbroken sandy appearance to the eye if the members are separated), and also when a plasticizing liquid is still present at the glue line.

The preliminary bond need be no more than 90

sufficient to hold the members together while the assembly is removed from the press and set aside for further action. Such preliminary bond may be formed by that portion of a difficultly plasticizable, slow-setting adhesive, which is first plasticized and set, or, desirably by a quick-setting adhesive included in the adhesive base material supplied. Such quick-setting adhesive may desirably be an albuminous material such, for example, as blood albumin. The conjoint use of blood albumin and soya-bean flour, casein, or the like is disclosed and claimed in the copending application of Theodore Williams Dike, Serial No. 455,978, filed May 28, 1930, and patented March 29, 1932, Patent No. 1,851,951, and no claim is made herein broadly to the conjoint use of such materials.

As difficultly plasticizable materials, reference may be made to casein, soya-bean flour, other oil-seed flours, etc. These are applied in discrete-particle form, preferably in powdered form. The quick-setting adhesive is desirably supplied also in powdered form, but in certain instances may be carried in a liquid vehicle.

A liquid, ordinarily water, is utilized in the plasticization of such material, and the liquid may be provided in any desired manner. The invention permits the liquid to exert its effect as the formation of the bond proceeds.

In accordance with the invention, moreover, a plasticization promoter is given an opportunity to exert its effect slowly while the plasticization and setting of the adhesive proceeds. Caustic soda is the preferred example of such a plasticization promoter. This material not only assists in the plasticization of the adhesive base, but also has a desirable effect on the fibres of the wood adjacent the glue line. Other plasticization-promoting materials such as hydroxides of other alkali metals, or, in some instances, alkaline earth hydroxides, such as lime, or other materials may be utilized. Such a plasticization promoter may be applied or produced at the glue line in any manner which may be desirable in a particular instance.

Preferably, in many instances, only a moderate heat is applied with the pressure, for example, heat in the neighborhood of 220° F. to 260° F. By avoiding high heats too rapid action at the glue line is prevented.

It is to be understood that the term "slow-setting adhesive", as used herein, is designed to cover an adhesive, the setting of which when applied in discrete-particle form is relatively slow, regardless of whether the slowness of the setting is due to slowness in obtaining complete plasticization or for other reasons.

As examples of procedures which may be carried out in accordance with the invention, reference is made to the following:

65 Three-ply panels may be formed of com-

mercially dry one-sixteenth inch birch veneer by supplying to one of each pair of surfaces water at the rate of 12 lbs. per thousand square feet of double glue line, soya-bean flour at the rate of 24 lbs. per thousand square feet of double glue line, and 10% caustic soda solution at the rate of 24 lbs. per thousand square feet of double glue line; forming an assembly; and placing the assembly in a hot plate press and applying pressure in the neighborhood of 200 lbs. pressure per square inch, and heat of approximately 230° F., for 40 seconds. The assembly is then removed and set aside while the plasticization and setting of the adhesive at the warm glue lines continues, forming a strong, secure bond.

Three-ply panels may be formed of commercially dry one-sixteenth inch birch veneer by applying to one of each pair of surfaces water at the rate of 12 pounds per thousand square feet of double glue line, a mixture of 80 parts of soya bean flour or powdered casein with 20 parts of powdered dried blood at the rate of 24 pounds per thousand square feet of double glue line, and a 10% sodium hydroxide solution at the rate of 24 pounds per 1,000 square feet of double glue line; forming an assembly; and subjecting the assembly in a hot plate press to pressure in the neighborhood of 200 pounds per square inch and a temperature of 230° F. for thirty seconds; and then removing the assembly from the press and permitting the plasticization and setting of the adhesive to proceed. The blood in this case provides an especially secure clamp for holding the members together.

As above indicated, the blood may be in certain instances included in the water applied, and may be so applied at a desired stage in the procedure.

In the drawing there is exemplified a form of apparatus and procedure which may be utilized in carrying out the invention. There is shown a conveyor 10 above which is a disseminating mechanism indicated diagrammatically at 11 and which may be of a form such as disclosed in the copending application of Louis G. Merritt and Ericsson H. Merritt, Serial No. 542,257, filed June 5, 1931. Ahead of and beyond this disseminating mechanism are spray means indicated diagrammatically at 12 and 13 and which may be of the type disclosed in the copending application of Ericsson H. Merritt and Richard W. Stanley, Serial No. 535,822, filed May 8, 1931. In the use of such an apparatus wooden "squares" or plies 14 are disposed in succession on the conveyor and carried under the spray means 12, whereby a liquid is applied to the upper surface thereof, thence under the disseminating means 11 whereby a powdered adhesive material, with or without the other ingredients in powdered

form, is applied thereto, and thence under the spray means 13 whereby the powdered materials are wet down by a spraying liquid. The "squares" 14 may be disposed one on top 5 of another and an additional "square" 15 disposed on the uppermost surface, as indicated. A "square" 15 may be disposed on "square" 14 and the partial assembly thus formed may be re-disposed on the conveyor 10 and moved under the mechanism 12, 11 and 13, or may be disposed on another conveyor and passed under similar means, and an additional "square" disposed thereon. Other procedures may be followed. A two- 15 ply or multiple-ply assembly thus formed may be inserted in the press indicated at 16 as a conventional plywood press, and subjected to heat and pressure, or may be subjected to pressure and heat.

20 Since certain changes may be made in carrying out the above process without departing from the scope of the invention it is intended that all matter contained in the above description shall be interpreted as illustrative 25 and not in a limiting sense.

It is also to be understood that the following claims are intended to cover all of the generic and specific features of the invention herein described, and all statements 30 of the scope of the invention which, as a matter of language, might be said to fall therebetween.

Having described my invention, what I claim as new and desire to secure by Letters 35 Patent, is:

1. The process of uniting a wood member and another member, which comprises providing between said members adhesive-base material in discrete-particle form, applying 40 heat and pressure for a period sufficient to form a preliminary bond between the members, discontinuing the application of heat and pressure while a layer of substantially independent particles remains between the members, and permitting the plasticization 45 and setting of the adhesive material to continue.

2. The process of uniting a wood member and another member, which comprises providing between said members adhesive-base material in discrete-particle form, applying heat and pressure for a period sufficient to form a preliminary bond between the members, a liquid being present, discontinuing the 50 application of heat and pressure while a layer of substantially independent particles remains between the members and while liquid is still present, and permitting the plasticization and setting of the adhesive material to continue.

3. The process of uniting a wood member and another member, which comprises providing between said members proteinous adhesive-base material in discrete-particle 55 form, applying heat and pressure for a pe-

riod sufficient to form a preliminary bond between the members, discontinuing the application of heat and pressure while a layer of substantially independent particles remains between the members, and permitting 70 the plasticization and setting of the adhesive material to continue.

4. The process of uniting a wood member and another member, which comprises providing between said members difficultly plasticizable adhesive-base material in discrete-particle form, applying heat and pressure for a period sufficient to form a preliminary bond between the members, a liquid being present, discontinuing the application of heat and pressure while a layer of substantially independent particles remains between the members and while liquid is still present, and permitting 80 the plasticization and setting of the adhesive material to continue.

5. The process of uniting a wood member and another member, which comprises providing between said members difficultly plasticizable adhesive-base material in discrete-particle form and a plasticization promoter, 90 applying heat and pressure for a period sufficient to form a preliminary bond between the members, a liquid being present, discontinuing the application of heat and pressure while a layer of substantially independent particles remains between the members, and while liquid is still present, and permitting 95 the plasticization and setting of the adhesive material to continue.

6. The process of uniting a wood member and another member, which comprises providing between said members powdered casein and a plasticization promoter, applying heat and pressure for a period sufficient to form a preliminary bond between the members, a liquid being present, discontinuing the application of heat and pressure while a layer of substantially independent particles remains between the members and while liquid is still present, and permitting the plasticization 105 and setting of the adhesive to continue.

7. The process of uniting a wood member and another member, which comprises providing between said members soya-bean flour and a plasticization promoter, applying heat and pressure for a period sufficient to form a preliminary bond between the members, a liquid being present, discontinuing the application of heat and pressure while a layer 110 of substantially independent particles remains between the members and while liquid is still present, and permitting the plasticization and setting of the adhesive to continue.

8. The process of uniting a wood member to another member involving the use of a slow-setting adhesive, which comprises providing between the members a slow-setting adhesive base and a quick-setting adhesive 130

- base, the slow-setting adhesive base being in discrete-particle form and a softening liquid therefor being provided, applying heat and pressure for a period sufficient to form a 5 preliminary bond between the members, discontinuing the application of heat and pressure, and maintaining the members free from pressure while the plasticization and setting of the slow-setting adhesive proceeds.
9. The process of uniting a wood member to another member involving the use of a slow-setting adhesive, which comprises providing between the members a slow-setting 15 adhesive base and an albuminous adhesive base, the slow-setting adhesive base being in discrete-particle form and a softening liquid therefor being provided, applying heat and pressure for a period sufficient to form a preliminary 20 bond between the members, discontinuing the application of heat and pressure, and maintaining the members free from pressure while the plasticization and setting of the slow-setting adhesive proceeds.
10. The process of uniting a wood member to another member involving the use of a slow-setting adhesive, which comprises providing between the members a slow-setting adhesive base and blood albumin, both of said 25 adhesive bases being applied in powdered form, applying heat and pressure for a period sufficient to form a preliminary bond between the members, discontinuing the application of heat and pressure, and maintaining the members free from pressure while the plasticization and setting of the slow-setting adhesive proceeds.
11. The process of uniting a wood member to another member involving the use of a slow-setting adhesive, which comprises providing between the members a slow-setting adhesive base and blood albumin, the slow-setting adhesive being applied in discrete-particle form and the blood albumin being 40 applied in a liquid vehicle, applying heat and pressure for a period sufficient to form a preliminary bond between the members, discontinuing the application of heat and pressure, and maintaining the members free from 45 pressure while the plasticization and setting of the slow-setting adhesive proceeds.
12. The process of uniting a wood member to another member, which comprises providing between the members adhesive-base material in discrete-particle form, applying to the members pressure and a moderate heat for periods sufficient to form a preliminary bond, discontinuing the application of heat and pressure while a layer of substantially 55 independent particles remains between the members, and permitting the plasticization and setting of the adhesive material to continue.
13. The process of uniting a wood member to another member involving the use of a 60 slow-setting adhesive, which comprises providing between the members difficultly plasticizable slow-setting adhesive-base material in discrete-particle form and a plasticization promoter and a quick-setting adhesive, applying to said members pressure and a moderate heat sufficient to form a preliminary bond between the members, a liquid being present, discontinuing the application of heat and pressure, and maintaining members free from pressure while the plasticization and setting of the slow-setting adhesive proceeds.
14. The process of uniting a wood member to another member involving the use of a slow-setting adhesive, which comprises providing between the members soya-bean flour and a plasticization promoter and an albuminous adhesive base, applying to said members pressure and a moderate heat sufficient to form a preliminary bond between the members, a liquid being present, discontinuing the application of heat and pressure, and maintaining members free from pressure while the plasticization and setting of the slow-setting adhesive proceeds.
15. The process of uniting a wood member to another member involving the use of a slow-setting adhesive, which comprises providing between the members powdered casein and a plasticization promoter and an albuminous adhesive base, applying to said members pressure and a moderate heat sufficient to form a preliminary bond between the members, a liquid being present, discontinuing the application of heat and pressure, and maintaining members free from pressure while the plasticization and setting of the slow-setting adhesive proceeds.
16. The process of forming plywood comprising thin outer plies, which comprises providing adhesive-base material in discrete-particle form between the members and forming an assembly, applying heat and pressure to the assembly for a period sufficient to form a preliminary bond between the members, discontinuing the application of heat and pressure while a layer of substantially independent particles remains at each glue line, and maintaining the assembly free from pressure while the plasticization and setting of the adhesive material continues.
17. The process of forming plywood comprising thin outer plies, which comprises providing difficultly plasticizable adhesive-base material in discrete-particle form between the members and forming an assembly, applying heat and pressure to the assembly for a period in the neighborhood of thirty to forty seconds, discontinuing the application of heat and pressure, and maintaining the assembly free from pressure while the plasticization and setting of the adhesive proceeds.
18. The process of forming plywood comprising thin outer plies, which comprises pro-

viding between the members slow-setting adhesive-base material in discrete-particle form and albuminous adhesive-base material, applying pressure and a moderate heat to the
5 assembly for a period sufficient to form a preliminary bond, discontinuing the application of heat and pressure, and maintaining the members free from pressure while the plasticization and setting of the slow-setting
10 adhesive proceeds.

In testimony whereof I affix my signature.
HARRY GALBER.
